UNITED STATES PATENT OFFICE.

FRITZ LOEFFLER, OF YONKERS, NEW YORK.

AUTOMOBILE.

Application filed April 13, 1920. Serial No. 373,600.

To all whom it may concern:

Be it known that I, FRITZ LOEFFLER, a citizen of Germany, residing at Yonkers, in the county of Westchester, State of New York, have invented certain new and useful improvements in Automobiles, of which the following is a description, reference being had to the accompanying drawing and to the figures of reference marked thereon.

10 This invention relates to an arrangement in automobiles in which all the drive elements actuated primarily by the motor, particularly the crank shaft and clutch, the transmission and a transverse shaft which actuates the drive wheels through universal joints, are assembled in a common housing or casing in such manner that the driving power is transmitted over the shortest path through the housing construction, all the 15 drive elements operating in a common oil bath, and in which the construction may be assembled and taken apart under the most favorable conditions with the prevention of jamming by reason of inaccurate position 20 of the axle or the like.

25 This invention relates further to an arrangement in automobiles in which the entire drive or the essential parts thereof are placed in an extended crank case in such manner that the support or bearing for the crank shaft and the transmission, as well as the points of support for the transverse shaft, without forming part of the housing, consist of one piece or are so connected with 30 each other by means of bolts that all driving forces arising are received in this assemblage, and this assemblage may be formed into a cover-like structure which can be inserted from above into the housing.

35 40 Another object of the invention is a carrying forward of this idea, which consists in that the cover-like structure is surrounded by a thin walled housing, preferably made of sheet metal, with which it may likewise be inserted into the vehicle body or frame which is also of sheet metal. The arrangement is such that the floor of the thin walled housing is removable in whole or in part. The invention is based on the fact that the space 45 available in the frame is greater than is required for enclosing the machine parts. The 50 amount of oil necessary for lubrication

would thus be lost in this large space, thus more oil must be carried than is absolutely necessary. Furthermore, it is of advantage 55 that it should be necessary to have only a small space, oil-tight.

This invention further relates to an arrangement whereby the connection of the drive wheels, which connection is either 60 rigid or movable, is located at the extended crank case or the cover-like structure. This cover is provided with an internal extension to a point at the floor of the sheet metal housing where at this point the rigid or 65 movable connection of the drive wheels is located. The purpose of the connection of the wheels to the crank case or to the cover-like structure is to completely transmit the power and to simplify and cheapen the 70 construction and assemblage, since the crank case or cover-like structure offers a better and more accurate point of engagement for the coupling, and the vehicle frame or body may be constructed with such accuracy, in 75 particular the drive by means of the transverse shaft and universal joint results in a more accurate alinement of the wheels with respect to the engine block.

Another object of this invention is an arrangement which utilizes this positioning of all the drive elements in a common housing in order to make them readily and easily accessible for assembling and disassembling and inspection. In an ordinarily constructed 80 motor vehicle, that is one with a universal joint, rear wheel drive, the parts of this drive are distributed at various points of the vehicle, being accessible to various degrees according to their position. In order to 85 reach them, it is sometimes required to remove the floor boards of the vehicle and sometimes to crawl under the vehicle, and sometimes to remove a whole machine part, for example, the motor, which operation is 90 both laborious and requires a great deal of time.

The housing has the function of supplying a connection or support and enclosing the mechanism. According to the invention, the entire driving unit can be assembled and tested under load outside of the housing. The entire driving mechanism is inserted 100 into the housing as a unit or, when desired,

the individual parts can be inserted successively. It is of advantage to assemble the driving parts with the cover-like member whereby the whole may be inserted into 5 the housing from above, a peripheral flange making tight the joint between the cover and the housing.

An automobile of very simple construction may be produced according to this invention 10 by stamping the entire vehicle body of sheet metal and dividing the space which is to receive the drive elements by one or more transverse walls which reinforce the vehicle body and divide it into a number of compartments. Preferably the control levers for the clutch and transmission and also the steering 15 rod connections are arranged on the cover-like structure, it, of course, being understood that where it may be necessary certain parts 20 may be cut out of the intermediate wall which, if desired may be made of yielding material in order to avoid jamming.

The weight of the assembled driving elements, which sometimes is the greater part 25 of the total weight of the vehicle, is transmitted directly to the wheels according to this invention by positioning the point or points of attachment for the wheel springs on the common structure of some part thereof. The control elements for the various 30 parts can also be arranged on this structure so that the resulting automobile may be nothing more than a sheet metal body provided with four wheels, in which body the 35 coverlike structure, the ball bearings and drive elements for actuating the vehicle are inserted.

The motor may be arranged as desired. For instance, with the motor parallel with 40 the vehicle axle, a shaft is provided transverse thereof so arranged that the crank shaft will drive the transverse shaft directly through a gear or chain transmission. This latter construction is particularly suited for 45 the assembling of all parts of the driving mechanism in the cover-like structure, which results in the advantage that there need be only parallel shaft bores in the cover-like structure. When several cylinders are used, 50 the clutch and transmission are arranged between two cranks. When the crank shaft drives the transverse shaft by means of the gear transmission, weight, space and expense may be saved by arranging the drive 55 gear for the transverse shaft on or concentric with the crank shaft, and thus causing it to have the additional function of a transmission gear, one transmission gear being thus eliminated.

60 These and other objects will in part be obvious and will in part be hereinafter more fully disclosed.

In the drawings:—

Figure 1 is a longitudinal section of an 65 arrangement in which the drive elements are

assembled into a cover-like structure which is inserted from above into the housing of sheet metal;

Fig. 2 is a section on the line 2—2 of Fig. 1;

Figs. 3 and 4 show another embodiment in section from the side on the line 3—3 in Fig. 4 from above;

Fig. 5 is a sectional view of a modification;

Fig. 6 is a longitudinal section illustrating the extended casing;

Fig. 7 is a front elevation of the vehicle to which my invention is applied;

Fig. 8 shows another modification of the invention with certain parts removed for clearer illustration;

Fig. 9 is a partial front elevation with parts broken away of Fig. 8.

Referring to Figs. 1 and 2, the crank 85 shaft A with the drive elements located thereon, particularly the clutch B, the transmission gear C, the drive gear D for the transverse shaft E and the transmission gears F and G, are journaled in a common support H. The counter-shaft J with the transmission gears L and M arranged on a slidable sleeve K are supported by the member N which, in the present case, is formed as an extension of or cover for the 95 corresponding crank shaft bearing. The two bearings O for the transverse shaft E are located on member P which is an extension of and suitably fastened to the cover member H. All the elements are united 100 into a unit which is similar to a cover and which is inserted from above into the housing R, which is made of sheet metal, a tight closure being made by the arcuate flange S. The housing is a part of the 105 vehicle body T which is subdivided by two walls U and V. Thus the driving mechanism is supported by the rigid intermediate members H, N and P which receive the motive force. The extensions Z of the transverse shaft E pass through the sides of the 110 casing at the openings W, resilient pipes being placed at these openings to prevent ingress of dust and dirt and loss of oil within the casing.

Figs. 3 and 4 illustrate a construction in which the motor (not shown) has two cranks between which the clutch and the transmission are arranged transversely with respect to the vehicle, thus parallel to the transverse shaft and directly actuating the wheels, so that the transverse shaft is driven directly by the gear transmission from the crank shaft. A' designates the crank shaft, B' the clutch, C' the transmission, J' the counter-shaft, and L' and M' the two slidable transmission gears which can be caused to mesh with the gears F' and G' on the crank situated on the crank shaft. A spur gear transmission is herein shown 120 125 130

in place of the usual bevel gear transmission connecting the crank shaft A' and the transverse shaft E', the transmission gear G' being used in connection with the spur gear transmission as a driving means therefore which eliminates one of the gear wheels usually used. The gears G' and G'' are continuously in engagement with each other. In this construction, a single support C⁴ is made use of which contains all the bearings and which is inserted from above into the housing R' which is made of sheet metal and has the flange S' for purposes of tight closure. The control lever is located on the support C⁴ and is accessible at the inner part of the vehicle. The forked lever D' actuates the chain of gears L' and M' which are slidable on the shaft J'. In order to avoid jamming, the surface E' of the common support C⁴ facing the interior of the vehicle is not rigidly connected to the intermediate wall V'; a closure is effected by means of the resilient connecting element F'.

Referring now to Fig. 5, the cover-like structure a⁵ supports the driving mechanism. Underneath this structure and surrounding the driving mechanism there is a housing preferably of sheet metal, together with which the cover structure can be inserted into the vehicle body c⁶. The bottom c⁵ of the housing b⁵ is formed so as to be entirely removable. Furthermore, a certain portion of the bottom may be arranged so as to be removable. There may be an opening closed by the cover portion d⁵ for inspection of the clutch and to drain off the oil. In order to make the bottom c⁵ or cover d⁵ accessible without removing the structure a⁵—b⁵, a removable cover f⁵ may be provided in the lower wall of the vehicle body.

Referring to Figs. 6 and 7, the extended crank case a⁶ is made of thin sheet metal; it is provided advantageously with an opening at the bottom which is closed by means of an accessible cover b⁶. The whole is inserted in the vehicle body c⁶ which is made of sheet metal. The vehicle wheel couplings are to be attached to the cover-like structure g⁶ which supports the bearings of the gearing. For this purpose the cover-like structure g⁶ is provided with an extension f⁶ at a suitable point which extends to the bottom of the housing. The lower coupling d⁶ which, for example, consists of a leaf spring is attached to the lower face of the extension f⁶, and the floor of the housing can be rigidly connected thereto. The upper wheel coupling is here shown as a rigid bar e⁶. The entire arrangement is shown diagrammatically in Fig. 7. The wheels o⁷ are here attached to supports n⁷ whose lower ends are coupled to the ends of springs d⁷, the upper ends thereof being connected by short couplings m⁷ to the rigid bar

e⁷. The transverse spring d⁷ is attached to the crank case or to the extension of the cover-like structure with the simultaneous attachment of the housing a⁷ through an opening of the vehicle body c⁷. Figure 6 70 illustrates the manner of mounting the control lever for the clutch, transmission and steering rod connections, on the cover-like structure. In this view, the upper rigid bar c⁸ is shown as forming a mounting 2 for the lower end of the steering knuckle rod 1 and the gear shift levers 6, 7 and 8 are provided with a standard type of hand control lever 9 pivotally mounted as at 10 on the cover-like structure g⁸. In a similar manner, this cover-like structure forms a mounting as at 13 for the pivotal pin 12 so that when the clutch lever 14 is operated, the connecting lever 11 will shift the clutch in the usual manner. 80

Fig. 8 shows how the cover-like structure surrounded by a thin walled housing can be inserted therewith into a shell-shaped vehicle body. h designates the cover-like structure; i the surrounding thin walled 90 housing, and l the usual automobile hood. Cast with the part h there is a hinge m⁸ about which all the driving elements, even including the motor n⁸, may be swung upward in the direction of the arrow o⁸ as indicated by dotted lines. When in this position, the casing i may be removed; thus all the elements will be exposed and accessible. In order to swing the parts as described it is necessary to release several connections, 95 for example, the connections n and q⁸ through which the benzine and exhaust gases pass, respectively. The steering column is also arranged on the crank case, and is provided according to the invention at 100 any point with a joint r which is easily uncoupled so that the upper portion of the steering column s can be drawn out of the range of oscillation.

In Fig. 9 it will be seen how the swinging 110 of the motor may be effected with respect to the driving operation of the wheels. As seen in this figure, the connection of the wheels t to the housing h—i is made by means of two transverse springs u. Before 115 swinging h—i outwardly, the wheels on both sides are removed by uncoupling spring bolts v and the lower spring removed. For this purpose the shaft w is slidably arranged within the inner coupling so that it may be 120 withdrawn together with the corresponding wheel. Instead of being slidable in the coupling a different arrangement may be provided, for example, a telescopic connection of two connecting elements outside of the inner 125 coupling. An abutment y is provided, preferably at the highest point of the removable mechanism to serve as a support for the same when it is swung out to rest upon any supporting means z (Fig. 8). 130

1,489,011

Having thus described the invention, what is claimed as new is:—

1. In a motor vehicle of the class described, the combination of a body forming an open-top housing, a unit cover for said body adapted to close the top of said housing, a motor mounted on said cover, clutch and transmission mechanism mounted on said cover, oppositely arranged front-drive shafts carried by said cover and extending through said body housing to directly drive the front wheels, and driving connections between said transmission mechanism and said front drive shafts whereby said cover absorbs all motor and transmission forces and reactions except the reaction of the torsional movement transmitted to front wheels. 50
2. In a motor vehicle of the class described, the combination of a body forming an open top housing, a unit cover depending from and into said housing to close the opening therein, a motor mounted on said cover, clutch, and transmission mechanism mounted on said cover, oppositely arranged front-drive shafts carried by said cover and extending through said body housing to directly drive the front wheels, and driving connections between said transmission mechanism and said front drive shafts, whereby 55 said cover absorbs all motor and transmission forces and reactions, except the reaction of the torsional movement transmitted to front wheels. 60
3. In a motor vehicle of the class described, the combination of a body forming an open-top housing, a unit cover for said body adapted to close the top of said housing, a motor mounted on said cover, clutch and transmission mechanism mounted on said cover, oppositely arranged front-drive shafts carried by said cover and extending through said body housing to directly drive the front wheels, driving connections between said transmission mechanism and said 65 front drive shafts, said cover providing also a support for the means for operating the clutch, gear shift and steering mechanism whereby said cover absorbs all motor, and transmission forces and reactions except the reaction of the torsional movement transmitted to front wheels. 70
4. In a motor vehicle of the class described, the combination of a body forming an open top housing, a unit cover for said body adapted to close the top of said housing, a motor mounted on said cover, clutch, transmission mechanism mounted on said cover, oppositely arranged front-drive shafts operatively connected to said mechanism and carried by said cover, said drive shafts 75 extending through said body housing, front wheels connected to said drive shafts, couplings for said wheels, and means carried by said cover for supporting said wheel couplings. 80
5. In a motor vehicle of the class described, the combination of a body forming an open top housing, a unit cover for said body adapted to close the top of said housing, a motor mounted on said cover, clutch, transmission mechanism mounted on said cover, oppositely arranged front-drive shafts operatively connected to said mechanism and carried by said cover, said drive shafts 85 extending through said body housing, said cover having a depending portion terminating adjacent the base of said housing, a spring carried by said depending portion and the bottom of said housing, a rigid rod carried by the top of said housing, and 90 wheels connected to the ends of said drive shafts and wheel carrying members carried by said spring and said rigid rod. 95
6. In a motor vehicle of the class described, the combination of a body forming an open-top housing, a unit cover for said body adapted to close the top of said housing, a motor mounted on said cover, clutch, transmission mechanism mounted on said cover, oppositely arranged drive shafts, and universal connections between said drive shafts and said mechanism. 100

In testimony whereof, I affix my signature.

FRITZ LOEFFLER.
